UNITED STATES PATENT OFFICE.

ADAM W. KAUFMAN, OF MILWAUKEE, WISCONSIN.

DESIGN FOR A SMOKE KIT.

Application filed March 26, 1925. Serial No. 12,886. Term of patent 7 years.

To all whom it may concern:

Be it known that I, ADAM W. KAUFMAN, a citizen of the United States, and a resident of Milwaukee, in the county of Milwaukee and State of Wisconsin, have invented a new and original and ornamental Design for Smoke Kit, of which the following is a specification, reference being had to the accompanying drawing, forming part thereof.

The drawing illustrates a perspective view of the smoke kit.

I claim:—

The ornamental design for a smoke kit, in testimony that I claim the foregoing I have hereunto set my hand at Milwaukee, in the county of Milwaukee and State of Wisconsin.

ADAM W. KAUFMAN.
